US0D1007073S

(12) **United States Design Patent** (10) **Patent No.:** **US D1,007,073 S**
(45) **Date of Patent:** **** Dec. 5, 2023**

(54) **SMART PET WATER FOUNTAIN**

(71) Applicant: **Shenzhen Chongleyuan Technology Co., Ltd.**, Shenzhen (CN)

(72) Inventor: **Yupei Huang**, Shenzhen (CN)

(73) Assignee: **Shenzhen Chongleyuan Technology Co., Ltd.**, Shenzhen (CN)

(**) Term: **15 Years**

(21) Appl. No.: **29/879,016**

(22) Filed: **Jun. 30, 2023**

(51) **LOC (14) Cl.** **30-03**
(52) **U.S. Cl.**

USPC **D30/132**
